UNITED STATES PATENT OFFICE.

JOHN S. HOLLIDAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

ALTERNATING-CURRENT SIGNALING APPARATUS FOR ELECTRIC RAILWAYS.

No. 878,139.

Specification of Letters Patent.

Patented Feb. 4, 1908.

Application filed June 28, 1907. Serial No. 381,218.

To all whom it may concern:

Be it known that I, JOHN S. HOLLIDAY, of Wilkinsburg, Allegheny county, Pennsylvania, have invented a new and useful Alternating-Current Signaling Apparatus for Electric Railways, of which the following is a full, clear, and exact description, reference being had to the accompanying drawings, forming part of this specification, in which—

Figures 1, 2, 3 and 4 are diagrams illustrating different forms of my invention.

This invention has relation to signaling systems for electric railways, where a single phase alternating current is used for propulsion, and a similar current either of the same or different frequency is used for signaling purposes, the object being to provide a system of this character so arranged that the propulsion current cannot operate the signals or interfere in any manner with their operation.

My invention consists essentially in a relay device for controlling the signals having its winding so constructed and connected as to be operated only by the signaling current, as hereinafter more fully described.

Referring to Fig. 1, the numeral 2 designates track rails, which are divided into insulated sections, as indicated at 3. 4 designates inductive bonds of well known character which connect the track rails at the ends of the blocks or sections. 5 indicates a single phase generator which supplies the conductors 6 from which the currents in the track circuits for signaling purposes are supplied or derived. 7 designates a single phase generator which supplied the conductor 8 from which the cars or other vehicles, one of which is indicated diagrammatically at 9, receives the supply of propulsion current. 10 designates a single phase transformer, the terminals of the primary coil of which are connected across the conductors 6. One terminal of the secondary coil of the transformer is connected to the two coils or windings 11 and 12 of the relay device 13 by a single conductor 13^a. The other terminals of these two coils are connected respectively to opposite track rails. The other terminal of the secondary coil of the transformer 10 is connected to the opposite track rails at the other end of the block from the relay 13, through the two conductors 14 and 15, one

of which, as 15 has included therein a suitable inductance 16. The movable member 13 of the relay is pivoted at 17, and operates a switch contact indicated at 17^a which controls the circuit of the signal 18. The two coils 11 and 12 are displaced with reference to each other, as indicated, and are connected in parallel in so far as the signaling current derived from the transformer 10 is concerned, but are in series with each other between the opposite track rails with respect to any propulsion current which may flow from one of the rails to the other. The effect of the inductance 16 in the conductor 15 is to change the phase relation of the current in the coil 12 with respect to that in the coil 11, so that said coils act upon the movable member 13 of the relay in the manner of a two-phase motor. If there is no train in the block, the relay is supplied with this two-phase current, and maintains its closed position, as shown in the drawings, thereby completing the signaling circuit, and holding the signal clear. When a train enters the block, the two rails are thereby connected, so that the current is transmitted to each of the windings 11 and 12 of the relay in the same phase. The two windings therefore exert no action on the relay, and its movable member opens by gravity, breaking the signal controlling circuit at 17^a, and causing the signal to go to its danger position. The relay will not be affected by any propulsion current which may flow through the windings 11 and 12, due to differences in potential of the two track rails, since in so far as such current is concerned, the two coils are in series between the track rails, and the current will flow through one coil to its junction with the other coil, and thence back through that coil to the other track rail of the lower potential. Any propulsion current which may flow through these coils by way of the conductors 14, 15 and 13^a, is equally ineffective to operate the relay because it comes to both these windings through the common wire 13^a. This arrangement and connection of the relay coils enables a single phase signaling current to be used in the track circuit for signaling purposes, and even though the propulsion current may be of the same frequency, there will be no interference with, or false operation of.

the relay by the propulsion current. The advantages of using a single phase source of supply for the signaling circuit will be apparent to those skilled in the art, since only two of the conductors 6 are required to produce the two-phase current in the signaling relay, while the relay and its connections may be reduced to a very simple form.

The arrangement shown in Fig. 2 is similar to that shown in Fig. 1, with the exception that instead of the transformer 10, an auto-transformer 10^a is employed which is connected by a conductor 19 with the conductors 14^a and 15^a which correspond to the conductors 14 and 15 of Fig. 1, 16^a being an inductance which is included in the conductor 15^a. In this form, the connected terminals of the two coils 11 and 12 are connected by a conductor 20 with one of the conductors 14^a and 15^a.

6. An advantage of this arrangement over that shown in Fig. 1, is that it dispenses with the conductor 13^a of Fig. 1 leading back from the relay to the transformer at the other end of the block.

25 In the arrangement shown in Fig. 3, a polarized or reversing relay is employed for controlling the two sets of contacts 21 and 22. In this form of relay, the movable contact-carrying member 23 is pivoted at 24, so as to assume the normal position shown in the figure, but to move in either direction under the action of the two windings 11 and 12. These windings together with the general arrangement of the circuits therefore are the same as those shown in Fig. 1, except that a reversing switch 25 is included in the conductors 14 and 15, whereby the inductance 16 can be connected in series with either winding 11 or 12, the direction of movement 40 of the relay depending upon which winding the inductance is connected in series with. The arrangement shown in Fig. 4 is similar to that shown in Fig. 3, except that an auto-transformer similar to that of Fig. 2 is used.

45 The advantage of the reversing relay shown in Figs. 3 and 4 will be apparent to those skilled in the art, since only two or three transmission lines or mains are required for its operation.

50 It will be obvious that various changes may be made by those skilled in the art without departing from the spirit and scope of my invention. Thus any suitable form of two-phase motor for operating the relay may be used, as the arrangement and combination of the parts may be changed.

What I claim is:

1. In an alternating current system for electric railways using alternating current for both signaling and propulsion purposes, a relay having two windings, and circuit connections therefor whereby the phase of the signaling current passing through said windings is split, while the phase of any propul-

sion current which may pass therethrough is 65 not changed; substantially as described.

2. In an alternating current system for electric railways using alternating current for both signaling and propulsion purposes, a relay having two windings which are in series with each other with respect to propulsion current which may flow from one rail to the other, and in parallel with respect to the signaling current, and means in series with one of said windings for changing the phase of the 75 signaling current passing therethrough; substantially as described.

3. In an alternating current system for electric railways using alternating current for both signaling and propulsion purposes, 80 a relay having two displaced windings connected in series across the track and in parallel with respect to the signaling current, and means for changing the phase of the signaling current in the two windings; substantially as described.

4. In an electric railway system using a single phase propulsion circuit, and a single phase signaling circuit, sectional rails, a relay having two sets of windings, means whereby 90 the phase of the signaling circuit passing through said windings is normally displaced, while the phase of any propulsion current passing therethrough is not changed, said windings being so connected that the presence of a train in the section put the currents in said windings in phase with each other; substantially as described.

5. In an alternating current system for electric railways, a relay having a contact-operating member movable in both directions from a central position, two sets of windings arranged to act on said member, an inductance, and means for connecting the inductance in series with either one of said 105 windings; substantially as described.

6. In an alternating current system for electric railways, a relay having a contact-operating member movable in both directions from a central position, two sets of 110 windings arranged to act on said member, means for displacing the phase in one of said windings, and means for including the phase displacing means in series with either of said windings; substantially as described.

7. In an alternating current system for electric railways, a single phase generator for supplying signaling current, two transmission lines or mains leading therefrom, sectional track rails, a polarized or reversing 120 relay having two windings connected to said rails and to the transmission lines, and means for displacing the current phase in either of said windings; substantially as described.

8. In alternating current signaling mechanism, a relay having a member movable in both directions from a central position, a

single phase generator, two transmission lines leading therefrom, a plurality of windings for actuating the relay and connected to the transmission lines, and means for 5 placing the phase in said windings to actuate said member in either direction; substantially as described.

In testimony whereof, I have hereunto set my hand.

JOHN S. HOLLIDAY.
